UNITED STATES PATENT OFFICE.

WILLIAM R. KINNEAR, OF NEW YORK, N. Y.

PORTABLE HOT-WATER RADIATOR.

No. 896,837.

Specification of Letters Patent. Patented Aug. 25, 1908.

Application filed December 15, 1903. Serial No. 185,325.

To all whom it may concern:

Be it known that I, WILLIAM R. KINNEAR, a citizen of the United States, residing at New York, in the State of New York, have 5 invented certain new and useful Improvements in Portable Hot-Water Radiators, of which the following is a specification.

My invention has for its object to provide an individually heated radiator which is portable in the sense that it is not fixed by permanent connection with a heating system, the radiator being constructed of sufficiently light structure to permit its removal from place to place.

15 My invention will be hereinafter fully described and its novelty particularly pointed out in the claims, reference being had to the accompanying drawings, in which

Figure 1 is a perspective view of a complete radiator embodying my present invention, Fig. 2 is a vertical longitudinal section of a portion thereof on an enlarged scale, Fig. 3 is a horizontal section through the heating unit of the radiator on a still larger scale.

25 Three classes of units are employed in the radiator, to wit: expansion units 1, preferably two in number and located at the ends of the radiator, and which also serve to radiate heat from the circulating medium; 30 simple radiating units 2 which vary in number according to the capacity of the radiator; and a heating unit 3, of which there is preferably but one, located at an intermediate position in the radiator. These units are 35 connected up into a single structure by upper and lower circulating passages 4 and 5, preferably formed by striking up bosses on adjacent walls of the respective units and uniting said bosses in a suitable manner.

40 When the units employ inner tubes 6 to provide central air flues, the circulating passages are continued across these air flues by deflecting the opposite walls of each tube inward and uniting them, all of which is fully 45 described in previous applications and Letters Patent in my name.

8 (Fig. 1) represent a gas burner by way of illustration which is supplied by a suitable connection and air mixer 9. The burner 8 is 50 located beneath the heating unit 3, and the latter is suitably constructed to provide chambers for the circulating medium (water) and alternating heat flues 10 for the heating gases arising from the burner 8. These alternating chambers and flues are multiplied as 55 may be desired by the use of inner tubes 11

of suitable number. Tubes 11 are supported in the heater and connected with the remaining spaces for the circulating medium by striking up bosses on the opposed faces on 60 the several parts and uniting these bosses as already described.

In order to space the walls of the water heating tubes within the heat flue and at the same time to increase the surface from which 65 the circulating medium may receive the heat, bosses 12 are formed upon the walls of the water tubes. Some of these bosses are arranged to project across the heat flues while others are arranged to project across the 70 chambers for the circulating medium.

The radiator constructed as above described is efficient and economical in operation. It is also convenient for use as it may be readily mounted upon suitable caster 75 legs. The expansion units are open at the top so that the circulating medium evaporates and supplies the desired amount of moisture to the air of the room. The heat flue is also open at the top.

Having described my invention what I claim as new therein is the following:

1. In an individually heated radiator embodying a plurality of connected and intercommunicating units; a heating unit comprising an open ended central heat flue, a water chamber surrounding the heat flue, a narrow water chamber formed of two approximately parallel walls located within and extending approximately the length of 85 90 the heat flue, in spaced relation to the walls of the latter, and provided at its top and bottom, on both sides, with circulating and sustaining connections with the water chamber surrounding the air flue.

2. In an individually heated radiator embodying a plurality of connected and intercommunicating units; a heating unit comprising an open ended central heat flue, a water chamber surrounding the heat flue, and a plurality of tubes located within and extending approximately the length of the heat flue in spaced relation to the walls of the latter, and provided at top and bottom with circulating and suspending connections 100 105 each with the other and with both sides of the water chamber surrounding the heat flue, the circulating connections of the tubes being horizontally aligned.

3. In combination with a radiator comprising a plurality of heat-radiating units, a heating unit comprising an open ended

central heat flue, a water chamber surrounding the heat flue, and a plurality of tubes located within and extending approximately the length of the heat flue, in spaced relation to the walls thereof, and provided with circulating and suspending connections one with the other and with opposite sides of the surrounding water chamber, both at top and bottom, and constructed with 5 low spacing lugs struck up from the metal of the tubes, holding the walls of the different parts in spaced relation and increasing the surface for the impingement of the medium employed for heating the circulating 10 medium.

4. In a sheet metal radiator a plurality of units united at top and bottom with circulat-

ing connections in horizontal alinement; one of the intermediate units comprising an open ended central heat flue, a water chamber surrounding said heat flue, and a tube located within and extending approximately the length of the heat flue, provided upon opposite sides at top and bottom with circulating and suspending connections with the water 20 chamber surrounding the heat flue, which said connections are in horizontal alinement with the connections between the other units. 25

The foregoing specification signed this 8th day of December 1903.

WILLIAM R. KINNEAR.
